UNITED STATES PATENT OFFICE.

LESLIE R. N. CARVALHO, OF BROOKLYN, NEW YORK, ASSIGNOR, BY MESNE ASSIGNMENTS, TO THE CLOSURE SERVICE COMPANY, A CORPORATION OF OHIO.

RECEPTACLE CLOSURE.

Application filed April 21, 1923. Serial No. 633,647.

To all whom it may concern:

Be it known that I, LESLIE R. N. CARVALHO, a citizen of the United States, residing at Brooklyn, in the county of Kings and 5 State of New York, have invented certain new and useful Improvements in Receptacle Closures, of which the following is a specification.

This invention relates to a receptacle closure, and is in the nature of an improvement upon the structure shown and described in my pending application, Serial 10 Number 511392 (my file C-116).

A particular object of the present improvement is to so construct the closure as to render it more adaptable for accommodating itself to a close fit following the contour of the receptacle and also to accommodate itself to receptacles varying in size within 15 appreciable limits.

A further and more detailed object is to provide a closure having a marginal flange portion adapted to surround a portion of the receptacle and to provide said flange 20 with a seam rendering the flange expansible and capable of expanding to accommodate itself to the contour of the receptacle and to adapt the flange to properly fit receptacles of varying size.

25 A further object is to provide a closure having a flange portion provided with a seam vertical thereof and said seam constituting an inward projection of the flange adapted to engage the receptacle and to thereby hold adjacent portions of the flange sprung out of engagement with the receptacle whereby to generate a resilient spring 30 pressure of said seam against the receptacle to prevent likelihood of accidental disengagement of the closure from the receptacle.

A further object is to provide a closure 35 having its flange portion constructed to include a retaining part adapted to be torn off therefrom, along a score line, for releasing the closure, and to provide a simple means for protecting the raw edge of the remainder of the flange, said means being incidentally of a character to reinforce the flange.

40 Other objects and aims of the invention, 50 more or less specific than those just referred to, will be in part obvious, and in part pointed out in the course of the following description of the elements, combinations, arrangements of parts and application of 55 principles constituting the invention, and

the scope of protection contemplated will be indicated in the appended claims.

In the accompanying drawings which are to be taken as a part of this specification, and in which I have shown only a preferred 60 form of embodiment of the invention.

Figure 1 is a side elevational view of a closure constructed in accordance with this invention, the same being shown partly in vertical section and illustrating the closure 65 in sealing position upon the receptacle.

Figures 2 and 3 are diagrammatic views 70 illustrating the manner in which the closure is adapted to spread when applied to a receptacle having tapering side walls, Figure 2 showing the condition of the closure just prior to application, and Figure 3 showing the condition after application.

Figure 4 is a detail perspective view illustrating the character of seam employed.

Figures 5 and 6 are views similar to Figures 2 and 3 but illustrating the manner in which the closure, after removal of the attaching portion, is adapted to spread for providing 80 frictional engagement with the receptacle to retain the closure against accidental displacement.

Figure 7 is a diagrammatic transverse 85 sectional view for illustrating the manner in which the closure grips the receptacle.

Figure 8 is a view similar to Figure 7 but illustrating a modified shape of the closure for providing greater frictional engagement between the closure and the receptacle.

Figure 9 is a fragmentary sectional view 90 illustrating the use of an outstanding bead upon the receptacle for carrying the score line which connects the attaching portion with the remainder of the closure flange, and

Figure 10 is a view similar to Figure 9 but illustrating the condition of the closure after the attaching portion is removed.

Referring to the drawings for describing 100 in detail the structure therein illustrated, the reference character L indicates the receptacle which, for convenience, may be understood to represent the upper portion of a ketchup or like bottle.

The closure consists of a cover portion G 105 and a flange portion H. These parts are preferably formed from two separate pieces of sheet metal seamed together. The piece forming the flange portion is connected together bent into cylindrical form and its 110

ends are seamed together by a seam 2 extending vertical of the closure. The cover portion is connected in position by means of an annular seam 3.

- 5 The seam 3 is preferably, though not necessarily, of a character such that it holds the cover and flange parts rigidly and immovably connected together. At the same time it provides an attractively rounded 10 edge surface 4 at the upper edge of the closure projecting above the uppermost surface of the cover serving at once to frame the cover and to protect against injury any lacquer, paint or other ornamentation carried 15 by the cover.

This seam also serves as an effective reinforcing element for retaining the closure against distortion at all times.

- 20 Within the closure and in fact forming a part thereof, resting against the inner surface of the cover, is a disk shaped gasket 5 of cork or other suitable gasket material, the same being held in position by frictional engagement with the walls of the flange portion H. In use this gasket is intended to 25 rest upon the upper edge surface of the receptacle.

- The flange portion H is made substantially smooth and uninterrupted throughout 30 its entire surface, and it may bear any suitable paint or lacquer, or may be ornamented in any appropriate manner. Its lower annular edge, which normally would extend straight downwardly about the receptacle to 35 a point slightly below the annular shoulder 1 of the receptacle is bent or flanged inwardly as at 7 to under-lie said shoulder and to thereby hold the closure against displacement.

- 40 The receptacle with which this closure is intended to be used preferably has its portion, as 27, above the shoulder 1, shaped to provide a slight upward taper which is effective in the practical use of the closure in 45 that it enables the upper portion of the taper to be sufficiently small so that the closure may be readily introduced thereover and so that the lower portions of the taper will produce a tight fit within the closure 50 when the closure is applied. The frictional grip of the closure against the tapering sides of the receptacle will be sufficient to hold the closure against accidental displacement, and this is of course particularly important when there is present only the temporary closure, that is the portion of the closure remaining after the lower or attaching portion 9 of the closure has been torn off 55 along the score line 8 in the manner described in said pending application.

- 60 It is a feature of the present improvement also to make the seam 2 so that it will permit of expansion and contraction of the flange portion of the closure such expansion 65 may be particularly desirable as a means to

enable a given size of closure to be used upon receptacles of varying sizes, also to enable the flange to accommodate itself to a substantially snug engagement with the tapering sides of the receptacle.

The inter-folding, or inter-locking, type of seam, is clearly indicated in Figures 4 and 7, as well adapted for this purpose since it permits the end portions of the material to move back and forth relative to each other without opening the seam.

The closure may be made of a diameter, relative to the receptacle, such that it may be readily introduced over the upper end of the receptacle, as indicated in Figure 2, but such that it must expand, particularly at its lower edge, as it is moved downwardly over the tapering sides of the receptacle. The expansion will be resisted by the natural resiliency of the material of which the closure is made so that when the closure has assumed its final sealing position, as in Figure 3, the flange will closely and firmly hug the receptacle. Thereafter the portion 7 of the flange may be bent into engagement beneath the shoulder 1 for holding the closure in sealing position.

When the attaching portion 9 has been torn off and the closure thereby released and slid upwardly off of the receptacle the temporary or remaining portion of the closure will return, or contract, to or near its original cylindrical position, as seen in Figure 5. In the subsequent temporary use of the closure it will be caused to spread or expand whenever it is slid downwardly on to the receptacle, as seen in Figure 6, and in this way a suitably resilient pressure is always present against the receptacle for frictionally retaining the temporary closure 105 against accidental displacement.

The annular seam 3 at the upper edge of the closure serves to hold said upper edge against expansion at all times while leaving the lower edge of the flange free to expand 110 as explained, so that said seam 3 is thus instrumental in giving to the closure the slight and attractive tapering shape following approximately the taper of the receptacle.

115 It will, of course, be understood that in producing the seam 2 the parts thereof are so arranged as to provide suitable open spaces, as indicated at 31, into which adjacent parts may crowd for facilitating expansion of the closure. The movement, however, is almost imperceptibly slight in most instances so that substantially no bulk is added to the seam.

120 By reference to the illustration Figure 7 it will be seen that the seam 2 is so constructed as to stand wholly interiorly of the flange where it constitutes an inwardly projecting rib which by engaging against the receptacle, and thereby holding out of 130

engagement with the receptacle portions, as 32, of the closure, enable said portions 32, by their resiliency, to store an energy when the closure is forced downwardly over 5 the receptacle, which energy will press the seam, and an opposite portion as 33 of the closure, resiliently against the receptacle and operate to maintain the pressure for frictionally holding the closure, particularly the temporary closure, upon the receptacle. Incidentally this provision also increases the capability of a given size of closure for properly accommodating itself upon receptacles of varying size.

15 The modification Figure 8 illustrates substantially the same subject matter as in Figure 7, but in addition suggests the presence of a plurality of contact points as 34—34 comprising indented portions of the 20 closure flange spaced apart around the closure and thereby providing resilient energy storing portions as 35—35 between them for accomplishing the same results, but in a somewhat increased quantity, as compared 25 with the structure set forth with regard to Figure 7.

In the modification Figures 9 and 10 is illustrated an arrangement of parts by which the score line, as 8, may be held away 30 from the side surface of the receptacle. In this instance an annular bead which is formed upon the closure, and which is here indicated by the reference character 36, is made to project outwardly of the closure 35 and the score line 8 is formed directly within this bead, preferably in the lower portion of the bead but at such locality as to be spaced away from the receptacle. By thus placing the score line it follows that when 40 the attaching portion 9 is removed then the raw edge as 37 left upon the temporary closure faces inwardly so that it is concealed and protected by the outer rounding surface of the bead. Furthermore, since the 45 surface 37 is made to stand out of contact with the surface of the receptacle it follows that when the temporary closure is being put on to and off of the receptacle said edge will not be likely to accumulate scrapings 50 from the side of the receptacle.

The lower edge of the closure will therefore be maintained clean and attractive.

As many changes could be made in this construction without departing from the 55 scope of the invention defined in the following claims, it is intended that all matter contained in the above description or shown in the above drawings shall be interpreted as illustrative only and not in a limiting 60 sense.

Having thus described the invention what I claim as new and desire to secure by Letters Patent is:—

1. A receptacle closure comprising a cover 65 part and a marginal flange part, said parts

being separately formed and seamed together, the flange part comprising a rectangular piece of sheet metal bent into cylindrical form and having its ends seamed together, and said seam being of a character 70 to permit expansion and contraction of said flange part.

2. A receptacle closure having a portion to over-lie the upper end of the receptacle and having a depending flange for lapping the side walls of the receptacle, and said flange having end portions seamed together by a seam permitting expansion of said flange 75 said expansion occurring within the seam.

3. A receptacle closure having a portion 80 to over-lie the upper end of the receptacle and having a depending flange for lapping the side walls of the receptacle, said flange having end portions seamed together by a seam of a character to permit expansion of 85 said flange, said flange having a portion at the lower edge thereof for engaging the receptacle to hold the closure in sealing position thereon, and means whereby said last mentioned portion is detachable from the 90 remainder of the flange to permit removal of the closure.

4. The combination with a receptacle having an upwardly tapering exterior wall surface, of a closure for said receptacle comprising a portion for overlying the upper end of the receptacle and a flange portion for engaging said tapering wall, and said flange having end portions seamed together by a seam of a character to permit expansion of 95 said flange for enabling said flange to fit itself closely to said tapering wall as the closure is moved onto the receptacle.

5. The combination with a receptacle having a tapering exterior wall surface, of a closure for said receptacle comprising a cover portion and a one-piece flange portion, a lower portion of said flange being adapted to be bent inwardly beneath a portion of the receptacle to thereby constitute holding 105 means to retain the closure in sealing position upon the receptacle, and means whereby said lower portion is adapted to be torn off from the remainder of the flange to permit removal of the closure from the receptacle, 110 and means whereby said flange portion is rendered elastic whereby to permit it to hug closely against said tapering wall surface of the receptacle.

6. A receptacle closure comprising a cover 120 part and a marginal flange part, said flange part having a seam therein of a character to permit expansibility of said flange part, and said seam providing a projection interiorly 125 of said flange part arranged to engage the receptacle and to thereby hold adjacent portions of the flange out of engagement with the receptacle, the flange being of a diameter to tightly engage the receptacle, and said portions adjacent the seam being resilient 130

to thereby provide a resilient frictional engagement of the flange against the receptacle.

7. A receptacle closure comprising a cover part and a marginal flange part, said flange being adapted to be telescoped downwardly over the side walls of the receptacle and having an annular attaching portion at the lower edge thereof for engaging the receptacle to hold the closure in sealing position, said flange also having an outstanding an-

nular bead thereon, and said bead having a score impressed therein whereby to render said attaching portion of the flange detachable at will.

15

In testimony whereof I affix my signature in the presence of two witnesses.

LESLIE R. N. CARVALHO.
